UNITED STATES PATENT OFFICE

WILLIAM OSCAR JOHNSON, OF DENVER, COLORADO

DESIGN FOR A SHOE

Application filed October 7, 1929. Serial No. 32,962. Term of patent 7 years.

To all whom it may concern:

Be it known that I, WILLIAM OSCAR JOHNSON, a citizen of the United States, residing at Denver, in the county of Denver and State of Colorado, have invented a new, original, and ornamental Design for Shoes, of which the following is a specification, reference being had to the accompanying drawing, forming part thereof.

The dominant feature of my design consists in the ornamentation on the shoe.

The figure is a plan view of a shoe, showing my new design.

I claim:

The ornamental design for a shoe, as shown and described.

WILLIAM OSCAR JOHNSON.
